BILLBOARD HAVING A WORKMAN'S PLAT-
FORM AND LADDER

Roger W. Olmsted, San Mateo, Calif.; Wells Fargo Bank & Union Trust Co., administrator of said Roger W. Olmsted, deceased, assignor to Lillian W. Olmsted, San Mateo, Calif.

Application February 8, 1945, Serial No. 576,889

6 Claims. (Cl. 40—125)

1

This invention relates to billboards or outdoor signboards of the large size commonly called twenty-four sheet poster panels which are used to display advertising matter within and adjacent to nearly all cities, towns and hamlets of the country, and the invention has for its principal object the provision of a simple, rigid structure of light weight which may easily be erected, taken apart and transported to and from sign sites.

Other advantages and features of my improved billboard will appear in the following description and accompanying drawings.

In the drawings,

Fig. 1 is a front elevation of my improved billboard as erected in place on a ground foundation.

Fig. 2 is a top or plan view of the billboard of Fig. 1.

Fig. 3 is an enlarged vertical section of the billboard of Fig. 1 as seen along the line 3—3 of Fig. 1.

Fig. 4 is a greatly enlarged plan view of one end of the working platform with portions shown in section, as seen along the line 4—4 of Fig. 3.

Fig. 5 is an enlarged vertical cross section of the signboard portion embraced between the lines 5—5 of Fig. 1.

Fig. 6 is an enlarged plan view of the leg-tie structure as taken along the line 6—6 of Fig. 3.

Fig. 7 is a detail showing the lower end of a step ladder locked to the working platform.

Briefly described, my improved billboard is a substantially all-metal structure designed for quick assembly and disassembly, light in weight yet of great strength, possessing the required features to expedite the posting and removal of "bills" or posters, and withal of pleasing appearance.

In the drawings, the illustration of the billboard chosen shows one erected upon a foundation supported on ground piers or anchor posts buried in the ground, but it is obvious that the same structure may be supported on the roof of a building by eliminating the ground piers or anchor posts, or the "board" proper with or without its working platform may be secured to any wall such as the side of a building or other supporting structure.

The main parts or sub-units of the structure comprise the sheet metal panel 1 for the poster, its marginal frame 2, the working platform 3, the base or metal grille 4, the four supporting steel posts 5, the four foundation beams 6, and the eight ground posts 7 with anchor blocks 8 attached to their lower ends. The entire structure thus consists of 28 sub-units, this being the greatest number of sub-units which would have to be

2

handled in erecting or taking down one of these billboards.

The foundation units, horizontally extending beams 6 and vertical anchor posts 7 are preferably of wood, the latter being preferably creosoted and secured as by iron straps 10 bolted or lagged to the wood as at 11, together with such additional stiffening braces as may be required for foundations of greater heights. The anchor blocks 8 may be of wood, preferably creosoted or of metal suitably secured to the anchor posts.

After placing the anchor posts in position and with beams 6 all on a level, the main posts 5 are bolted in place by bolts 23 in holes already provided in beams 6. After this the long platform 3, permanently secured to four angle bars 13, is bolted to the main posts by bolts 14. The grille 4 permanently secured to its angle iron supporting bars 15 is placed in position and the bolts 9 passed through the overlapping ends of bars 13 and 15, and the lower ends of bars 15 are bolted by bolts 16 to the ends of the horizontal tie channel members 17 of the main posts 5. After this the sheet metal poster panel 1, and its frame 2 are erected, section by section, starting at the top and finishing with the two ends, securing each horizontal section to the main posts as by special hook bolts 18 which pass through the flanges 19 of the posts.

After the structure has once been assembled on its foundation it does not have to be taken apart again when shifting it to another location which is a frequent occurrence in the operations of every outdoor advertising business. The entire structure after removing bolts 23 may be lifted from its foundation beams 6 with a light motor crane or other hoisting equipment. The structure may then be placed in an upright position on a low bed trailer or carried suspended by the motor crane to another location or site and placed on another previously prepared foundation, the great rigidity of the present structure permitting such handling, and sling attaching holes 34 are provided in posts 5 for this purpose.

The main posts 5 as shown in the drawings are of specially formed sheet metal channel beams with their flanges turned inward at their outer edges as shown at 5' in the drawing so as to provide added strength and rigidity with light gage metal and also make them easier to handle without damage.

For about one-half of their height from the bottom these posts are made double by placing two of the special channels back to back, and secured together as by bolts 20, and from the

lower edge of the marginal frame 2 the doubled channels are reversely bent edgewise so as to form a pair of inverted V-legs 5" with about a five foot spread, and the lower ends of the channel legs are cut-off on a horizontal line, their flanges removed for a short distance so that they will fit between and can be secured to a pair of specially formed sheet metal channels 17 as by bolts 21 or otherwise so as to provide a base for post 5. A filler strip 22 or thick washers being interposed at opposite sides of legs 5" as shown best in Fig. 6 to allow for the offset of the legs and also to provide room for the main foundation bolts 23. Preferably the bolts 23 are provided with heavy washer plates 24 to distribute the load. Channels 17 are formed with reentrant flanges the same as described for posts 5.

Posts 5 and their bases 17 are made symmetrical so that another poster panel 1 and marginal frame 2, platform 3 and grille 4 may be erected on the back side of the framework after first removing the erecting lugs 30 thereby providing two billboards on a single frame which is very often desirable.

The poster panel 1 is here shown as made of a series of interlocking sheet metal sections running lengthwise of the billboard. These sections are stiffened by forming continuous U-shaped flanges along each horizontal edge, one flange being slightly larger than the other so that the top flange of one section will fit neatly and snugly inside the bottom flange of another section as shown in Fig. 5 at 25 and 26. The sections are secured to the main posts 5 by means of hook bolts 18 fastened over the nested flanged edges of the sheet metal sections as shown in Fig. 5.

The marginal frame 2 which surrounds the sheet metal poster panel 1 is also made of sheet metal formed with reentrant flanged edges 25' similar to the flanged edges of the sheet metal sections so that they will fit neatly and snugly to the sheet metal sections as best shown in Fig. 5, the depth of the flange, however, being considerably deeper than the sheet metal sections of the poster panel 1 so that the frame will project forward of the poster panel so as to provide a working guide in applying and scraping off the posters and to protect the edges of the poster against damage from rain or from water resulting from the frequent washing of the marginal frame 2.

The juncture between the ends of the sheet metal sections of the poster panel 1 and the marginal frame 2 may be made with plain flanges on the adjacent members as shown in Fig. 4 at 27 and 28 secured together by through-bolts 29.

The marginal frame 2 is preferably made with rounding corners 2' as it provides easier handling while at the same time presenting an attractive appearance. The face of the frame is provided with one or more hollow sheet metal molding strips 31 running completely around the frame bolted or otherwise secured thereto, and held spaced away from the frame a short distance by means of thick washers 33 so as to facilitate both the washing and the painting of the frame should it be desired to paint the molding strips a different color than the frame itself.

To provide for the erecting of the poster panel 1 and its marginal frame 2 short sections of Z bars 30 are bolted at spaced intervals on the rear flanges of the posts. The Z bars are of a size to easily receive long temporary horizontal joists 75

or "two by fours" for the erecting crew to climb and stand on, and which joists are removed when the job is completed.

The long working platform or runway 3 which is provided for the bill posters to stand on while placing or removing posters from the panel or when washing or painting the marginal frame, is preferably made of heavy strips of lumber well painted all over and held in place by screws or bolts (not shown) passing through the angle bars 13, an inner guard strip 3' being provided at the inner edge of the platform and an open gap 32 provided for the length of the platform adjacent the frame 2 in which the inner legs of a step ladder or the supports for a trestle may be safely locked (as indicated in Fig. 7) while the bill posters or other workmen are posting, painting or washing the upper parts of the billboard. The platform extends somewhat beyond the marginal frame 2 at both ends as shown in the drawing and therefore considerably beyond the poster panel 1 so that the workmen can conveniently post, paint or wash the billboard without excessive reaching.

In Fig. 7 is shown one way of locking a step ladder to the slot or gap 32 of the working platform 3. In this showing the ladder 35 is a step ladder arranged with its rungs 36 extending at right angles to the platform 3 and with the leg 35 adjacent the sign panel made longer and with a pair of angle plates 37 secured to it to form a stop against the platform and a suitable latch or turn-bolt 38 rotatably supported on the leg as at 39 arranged to engage the underside of the platform to prevent withdrawal of the leg until the latch is released. This locking device or its equivalent may be on both inner legs of the step ladder if desired, or applied to a common straight ladder, and it is manifest that it may be varied considerably from the lock shown which is only to be considered illustrative. The grille 4 is preferably made of sheet metal pressed with a wide channel marginal rim 4' and intermediate spaced ribs or corrugations 4 and with a series of spaced open slots 4". This makes a very rigid, yet handsome grille, and meets the legal requirements of transparency required in some cities. The sheet metal grille is secured permanently to vertical angle bars 15 spaced opposite the posts 5 and at the two ends, these bars acting both as supports for the outer edge of the platform 3 and as stiffeners for the sheet metal grille.

With the construction as described, it will readily be seen that the assembly is very easily erected or taken down, and even with ordinary workmanship the parts are readily interchangeable with like parts, and hence no separation or grouping of the parts in "sets" is required in the warehouse, and when repairs are required due to injury to part of one of the installations from any cause, the injured sub-unit alone is removed and replaced with a new sub-unit without disturbing the remainder of the installation.

From the above description, it will be evident that various minor changes in detail may be made without affecting the structure as a whole and as may fall within the scope of my appended claims.

I claim:

1. In a billboard structure having a sign panel, a workman's platform secured to and extending substantially the length of the billboard structure horizontally below and forward of the sign panel, a longitudinal slot in said platform adjacent the sign panel arranged and adapted for

securing of a ladder to the platform for sliding therealong adjacent the sign panel.

2. In an outdoor billboard structure a poster receiving panel, said panel provided with a channel-shaped sheet metal frame extending entirely around its edge with its web in front and provided with sheet metal moulding strips secured to its outer exposed surface and spaced forwardly from said surface to permit painting thereunder.

3. In a billboard structure of the character described and having upright posts spaced along the rear side of and to support the poster panel, said posts formed of metal having channel cross section with their webs extending at right angles to the plane of the panel and with the lower portion of each post bent edgewise forwardly to extend under the poster panel, and a shorter length of a similar channel post secured back to back to the lower part of each post and bent edgewise rearwardly to cooperate with the forwardly bent portion in forming a pair of diverging legs for each post.

4. In a billboard structure of the character described and having upright posts to support the poster panel, said posts formed of metal having channel cross section and with the lower portion of each post bent edgewise forwardly to extend under the poster panel, and a shorter length of a similar channel post secured back to back to the lower part of each post and bent edgewise rearwardly to cooperate with the forwardly bent portion in forming a pair of diverging legs for each post, and a pair of tie bars extending horizontally at the lower ends of said legs embracing opposite sides thereof and secured thereto and provided with means for securing the tie bars to a foundation.

5. In a billboard structure as set out in claim 1 a ladder provided with means adapted to project through said slot for locking the ladder to the platform at any point along the slot against toppling over.

6. An outdoor billboard comprising a plurality of horizontally spaced upright posts arranged in alignment, a poster receiving panel removably secured to said posts, braces secured to and projecting horizontally forward from said posts below said panel, a workman's platform extending along below the panel secured to and carried on said braces, said posts each provided with inverted V-shaped spreading legs with one extending under said platform and the other rearwardly and all being symmetrical so as to accommodate another poster panel and platform at the rear of said posts.

ROGER W. OLMSTED.
